SHELTER FOR HOUSING MULTIPLE TELEPHONE STATIONS

Keith D. Bartley, Indianapolis, Ind., Henry Dreyfuss,
South Pasadena, Calif., and Robert E. Prescott, Rum-
son, N.J., assignors to Bell Telephone Laboratories, In-
corporated, New York, N.Y., a corporation of New
York

Filed Sept. 21, 1964, Ser. No. 81,790

Term of patent 14 years

(Cl. D13—1)

FIG. 1 is a perspective front and side view of a shelter for housing multiple telephone stations embodying our new design;

FIG. 2 is a front elevation thereof; and

FIG. 3 is a side elevation thereof.

The broken line showing in the several views are disclosed for illustrative purposes only. The rear of the article is substantially the same as the front, as shown in FIG. 2.

We claim:

The ornamental design for a shelter for housing multiple telephone stations, substantially as shown and described.
